CLAIM

We claim the ornamental design for a display stand, as shown and described.

DESCRIPTION

FIG. 1 is a front perspective view of a display stand showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and

FIG. 7 is a bottom view thereof;

FIG. 8 is a rear environmental perspective view thereof supporting a display in a middle height position;

FIG. 9 is a rear environmental perspective view thereof supporting a display in an upper height position; and,

FIG. 10 is a rear environmental perspective view thereof supporting a display in a low height position.

The broken lines shown in FIGS. 1–7 illustrate portions of the display stand that form no part of the claimed design.

(Continued)

The broken lines illustrating the monitor in FIGS. 8-10 are environment, while the remaining broken lines in FIGS. 8-10 illustrate portions of the display stand that form no part of the claimed design.

1 Claim, 10 Drawing Sheets
